DESIGN FOR A DESK OR SIMILAR ARTICLE

Joseph R. Bate, Manitowoc, Wis., assignor to Invincible Metal Furniture Company, Manitowoc, Wis., a corporation of Wisconsin

Application April 6, 1936, Serial No. 61,968

Term of patent 14 years

To all whom it may concern:

Be it known that I, Joseph R. Bate, a citizen of the United States, residing at Manitowoc, in the county of Manitowoc and State of Wisconsin, have invented a new, original, and ornamental Design for Desks or Similar Articles, of which the following is a specification, reference being had to the accompanying drawing, forming part thereof.

Figures 1 and 2, are respectively, front and rear perspective views of a desk, showing my new design.

I claim:

The ornamental design for a desk or similar article, as shown.

JOSEPH R. BATE.
